United States Patent Office.

JOHN HALL, JR., OF TEMPERANCEVILLE, PENNSYLVANIA.

Letters Patent No. 102,814, dated May 10, 1870.

IMPROVEMENT IN POTATO-DIGGERS.

The Schedule referred to in these Letters Patent and making part of the same.

To all whom it may concern:

Be it known that I, JOHN HALL, JR., of Temperanceville, in the county of Allegheny and State of Pennsylvania, have invented a certain new and useful Improvement in Potato-Diggers; and I do hereby declare that the following is a full, clear, and exact description thereof, reference being had to the accompanying drawings and to the letters of reference marked thereon.

The nature of my invention consists in the combination and arrangement of a shovel-plow, separator, and agitator-wheel constructed, arranged, combined, and operating, as hereinafter described.

To enable others skilled in the art to make and use my invention, I will proceed to describe its construction and operation.

In the accompanying drawings, which form part of my specification—

Figure 1, sheet A, is a vertical and longitudinal section of my improvement in potato-diggers.

Figure 2 is a perspective view of the digger or mold-board.

Figure 3 is a perspective view of the separator.

Figure 4, sheet B, is a top or plan view of my improvement in potato-diggers.

In the accompanying drawings—

A represents the digger or mold-board, the face of which is made concave, as shown in figs. 1 and 2, and is secured to the curved standards B, to which the handles D are attached.

To the handles D and standards B are attached braces e, for giving stiffness and strength to the handles; to the upper and front ends of the standards B is welded the beam C, the front end of which is provided with a hanger, f, in the lower end of which is pivoted a wheel, h.

The hanger f is braced with relation to the beam C by means of a brace, g, and both hanger and brace are held in the desired position to the beam C by means of the bolts J and i, and the openings marked 3. The hanger f, with its wheel h, is used for the purpose of regulating the depth of digging.

To the back end of the digger or mold-board A is pivoted at l, a separator, which consists of a series of parallel rods, K, attached to two transverse rods, f', and w.

The rod w is provided with a small friction-roller, S, against which the arms 2 of the agitator-wheel n act when the digger is in operation.

The agitator-wheel n is pivoted in the piece o, which

is secured to the back part of the digger or mold-board A.

To the separator, and over the agitator-wheel n, is secured a guard, m, which is used for the purpose of preventing the agitator-wheel n from becoming clogged with weeds, dirt, or potato-tops.

As the construction and arrangement of the several parts of my improvement, and the relation they bear to each other, will be readily understood from the foregoing description, and by reference to the accompanying drawings, I will therefore proceed to describe the operation.

I adjust the hanger f and brace g so that it will allow the digger A to enter the ground to the desired depth. The forward movement of the digger will divide the potato-hill, and the face of the digger being concave, the potatoes will be gathered toward the center of it, and will pass back between the standards B onto the separator, which, being agitated through the medium of the agitating-wheel n, will cause the earth to pass down between the rods K of the separator, and thereby separate the potatoes from the earth, and the concave surface of the separator will so gather the potatoes together as to deposit them in a row on the surface of the ground.

By attaching the digger or mold-board A to the standards B, as herein described and represented, a free passage between the standards is obtained, and the digger is not liable to become clogged with dirt, weeds, or potato-tops. By means of the concavity in the face of the digger A, the potato-hills will be so divided, as that the potatoes will be thrown back on the central portion of the separator, which, being also provided with a concaved surface, will deposit the potatoes on the ground separated from the earth, and gathered together in rows.

By the use of the guard m the agitating-wheel is protected from weeds, potato-tops, and other matter liable to clog it, and make it inoperative.

Having thus described the nature, construction, and operation of my improvement,

What I claim as of my invention, is—

The combination of the concave plow A, the concave separator, provided with the guard m, and agitator-wheel n, constructed, arranged, and operating substantially as herein described, and for the purpose set forth.
